UNITED STATES PATENT OFFICE.

JOHN COOPER, OF NEW YORK, N. Y.

DESIGN FOR A CHIMNEY-CAP MEMBER.

SPECIFICATION forming part of Design No. 32,452, dated April 3, 1900.

Application filed March 7, 1900. Serial No. 7,745. Term of patent 14 years.

To all whom it may concern:

Be it known that I, JOHN COOPEE, a citizen of the United States, and a resident of the city of New York, borough of Brooklyn, in the county of Kings and State of New York, have invented and produced a new and original Design for a Chimney-Cap Member, of which the following is a full, clear, and exact description.

Reference is to be had to the accompanying drawings, forming a part of this specification, in which similar characters of reference indicate corresponding parts in both the figures.

The essential feature of my design for a chimney-cap member consists in a rectangular plate 3, having extended through it a rectangular opening 4, and upon the upper edge of this plate 3 and arranged at right angles to each other are beads or ribs 5 6, the lower surfaces of which are projected outward substantially on a plane with the upper surface of the plate 3. The minor feature of the design consists in transversely curving or rounding the upper surfaces of said ribs or beads and forming narrow beads 7 on the lower surface and also forming the grooves 8 in the upper surface of the member. It will also be noted that the width of the material is reduced at the sides occupied by the ribs 5.

Having thus described my invention, I claim as new and desire to secure by Letters Patent—

The design for a chimney-cap member, as herein shown and described.

In testimony whereof I have signed my name to this specification in the presence of two subscribing witnesses.

JOHN COOPER.
